UNITED STATES PATENT OFFICE.

FRIEDRICH HAUPTVOGEL, OF VIENNA, AUSTRIA.

APPARATUS FOR THE PREVENTION OF INCRUSTATIONS AND CORROSION ON METALLIC SURFACES.

Application filed April 17, 1925, Serial No. 23,993, and in Belgium May 10, 1924.

The invention relates to the prevention of incrustation and corrosion in steam boilers, condensers and like apparatus.

Methods exist for electrically preventing the formation of incrustation and corrosion in steam boilers, condensers and other similar vessels. Such methods consist essentially in including the boiler or other vessel to be protected in an electric circuit. They are all based on the recognition that the formation of incrustation and corrosion in boilers, etc. is to be attributed to the fact that the impurities separating as a result of the vaporization of the water are deposited in the state of solid incrustation on the walls of the boiler under the action of electric currents fortuitously occurring inside the boiler, from a variety of causes including possibly internal electrolytic action. In order to attempt to neutralize the action of these fortuitous electric currents, a direct current is sent through the boiler, etc. which thus tends to prevent the deposit of such incrusting materials and corrosion.

However these previous methods have for various reasons not given satisfactory results. Such known methods, consisting for example in causing a direct current to pass by means of electrodes through the water of the boiler, necessitate drilling the wall of the boiler, etc. at at least two points for the introduction of electrodes. It is obvious that such holes must be made water-tight, with due regard to the steam pressure, and must moreover be provided with electric insulation, which renders the application of the method appreciably complicated and costly, especially when it is considered that the electrodes, in particular the anode is used up rapidly and must therefore be renewed after relatively short service.

In carrying out the invention, the boiler or other vessel to be protected is mounted in a separate constantly loaded circuit, branched from the two leads of a main electric supply network, the boiler being mounted in parallel with a variable resistance serving to determine the strength of the necessary current. Measures are moreover taken to indicate immediately faults due to earthing occurring in the mains.

Figure 1 of the drawing shows diagram-

matically the connection according to the invention.

Figure 2 illustrates the case when the positive lead is grounded. 55

Figure 3 illustrates the case when the negative lead is grounded.

Figure 4 illustrates the connection of a signal lamp in both positive and negative 60 leads.

Fig. 1 of the annexed drawing shows diagrammatically this new method of placing in circuit the boiler to be protected as well as the disposition of the resistance for obtaining a suitable current strength and potential. The boiler to be protected is designated K, and is mounted in a shunt circuit branched at a and b from the main network. In this circuit is included between a₁ and b₁ a 70 variable resistance W enabling the above mentioned regulation of the necessary drop of potential. There is also provided in each lead of the circuit a fuse S₁, S₂ and in one of them a lamp L or other signalling device 75 serving to indicate normal functioning of the installation.

However with this circuit arrangement, it is possible that in the event of grounding of one or the other of the conductors of the 80 main network, the arrangement would be inoperative although the signal lamp is lighted. If for example, as shown in Fig. 2, the positive conductor of the network is grounded, there is established, besides the 85 arranged operative circuit, a second circuit passing by b, the earth, the boiler K connected electrically to earth, then by a₁, S₁ and a. But as no resistance is included in such additional circuit, there is immediately 90 produced by this path a short circuit, such that the fuse S₁ melts and the signal lamp L, no longer receiving current, becomes extinguished. However this is the least dangerous case, as the extinction of the signal lamp draws attention to the derangement. 95

It is quite otherwise when the grounding is not complete, i. e. the circuit still is partly insulated from the earth. In this case the 100 strength of the current in the circuit b, earth, boiler, a₁, S₁, a increases up to a certain value, limited in this insulation which current in many cases does not cause

melting of the fuse S_1 but is sufficient to make the installation inoperative. Practice has shown that the electric currents which are formed within the boiler can only 5 be neutralized by currents of the approximately same strength. If the strength of the current passing through the boiler is too great, the apparatus becomes inoperative. However the lamp L continues in such 10 case to burn, provided the two fuses S_1 and S_2 remain intact.

The same conditions occur in Fig. 3, wherein the negative pole is grounded. In 15 this case, the melting of the fuses does not occur at all, as the lamp is in series with the boiler and the grounded conductor. However in this case the current passing through the boiler is too heavy and inoperative when 20 the grounding is complete.

It is therefore necessary to include in the 25 second conductor of the shunt a signal lamp or similar device, as shown at Fig. 4. One of the lamps is designated by L_1 and the other by L_2 , and it is seen that during normal operation, the two lamps give the same 30 luminosity of partial intensity, whilst in the event of grounding of one or the other of the conductors, the corresponding lamp burns immediately with its full intensity and the other lamp immediately extinguishes so that

the attention of the personnel is drawn to the derangement which has occurred.

What I claim is:

1. In an apparatus for protecting metallic surfaces against incrustations comprising 35 a direct current circuit, a shunt circuit derived from said direct current circuit, which shunt circuit contains in series constant resistances in the form of incandescent lamps and an adjustable resistance and a second 40 shunt circuit derived from said adjustable resistance and containing said surface to be protected.

2. In an apparatus for protecting metallic surfaces against incrustations comprising 45 a direct current source of supply, a circuit in shunt with said direct current source of supply comprising a plurality of constant resistance elements in series, a second circuit in shunt with said first shunt circuit and 50 connected at one of its terminals to one of said resistance elements by adjustable means to selectively adjust the point of connection with such resistance element, said second shunt circuit containing the surface to be 55 protected.

In testimony whereof I have signed my name to this specification.

FRIEDRICH HAUPTVOGEL.
